UNITED STATES PATENT OFFICE.

HERMAN A. AGRICOLA, JR., OF ATLANTA, GEORGIA, ASSIGNEE OF ONE-FOURTH TO
JOSEPH E. LANE AND TWENTY-FOUR PER CENT TO H. V. GARRETT, BOTH OF AT-
LANTA, GEORGIA.

PRINTING-PRESS ATTACHMENT.

Application filed October 30, 1920, Serial No. 420,627. Renewed June 20, 1923.

To all whom it may concern:

Be it known that I, HERMAN A. AGRICOLA, Jr., a citizen of the United States, residing at Atlanta, county of Fulton, and State of Georgia, have invented certain new and useful Improvements in Printing-Press Attachments, of which the following is a specification.

This invention relates to an attachment 10 for printing presses whereby multicolor work may be run off upon a press of any standard kind.

For its objects my invention aims to provide an attachment which is adapted to 15 perform multicolor work in a simple, effective and certain manner; an attachment which is simple and substantial in its construction; and an attachment for the purpose specified which subserves in a satisfactory manner the usual requirements of 20 a machine intended for multicolor work. Other objects and uses of this invention are hereinafter set forth in the specification wherein reference is made to the accompanying drawings which exhibit a preferred embodiment of my invention in association with a printing press in the manner following:

Figure 1 is a side elevation of the upper 30 portion of a printing press of any conventional kind;

Fig. 2 is a front elevation thereof;

Fig. 3 is a longitudinal section through the printing rollers taken on line 3—3 of 35 Fig. 7;

Fig. 4 is a fragmentary detail of the mounting for one of the roller wheels;

Fig. 5 is a longitudinal section taken on line 5—5 of Fig. 7;

Fig. 6 is a sectional detail taken on line 40 6—6 of Fig. 9;

Figs. 7, 8, and 9 are transverse sections taken, respectively, on lines 7—7, 8—8, and 45 9—9 of Fig. 3;

Fig. 10 is a view in elevation of the inner 50 face of one of the inking blocks;

Figs. 11, 12, and 13 are similar views of other inking blocks that are arranged complementary to the block of Fig. 10;

Fig. 14 is an elevation of the rear side 55 of the block shown in Fig. 13; and

Fig. 15 is a transverse section taken approximately on line 15—15 of Fig. 13.

I would have it understood that the at-

achment of this invention is applicable to 55 printing presses of different kinds, such, for instance, as rotary, flat bed, etc. For purposes of exemplification, I have represented in Figs. 1 and 2 a job press A pivoted to oscillate about a horizontal axis through 60 the medium of a pitman B which derives motion from a suitable power source. Mounted on the press are the usual rocker arms C arranged to oscillate about an axis D, the means for effecting such oscillations being of any suitable kind. These arms C which lie upon opposite sides of the press are connected as by means of a plate E on which is carried a pair of brackets F for pivotally supporting two links G which are adjustably connected as at H with rocker arms I pivoted at J to swing upon a suitable bracket or support K. At the end of each rocker arm opposite the connection H is a pivotal connection L with 70 an arm to which is secured a turnbuckle N which also connects with another arm section O. The parts thus connected are adapted to reciprocate upon the forward side of the press a carriage P whose construction in detail will presently be described. In the kind of press shown, the carriage moves in a straight line wholly upon the front of the press, but the carriage may take other courses of travel, such, for instance, as circular, or angular; or, in the case of a rotary press, relative movement 75 may obtain with the carriage remaining stationary.

80 Mounted in the carriage are the parts composing this invention, shown most comprehensively, perhaps, in Fig. 3. On each of the opposite sides of the bed of the press I arrange a guide block 20 recessed as at 85 21 to provide a shoulder 22, the block being formed on its opposite side with a rack 23. The carriage includes in its construction a pair of ends 24 each recessed to provide a seat 25, connecting bars 26 extending between the ends, as shown. In 90 operative relation to each guide block are a plurality of wheels 27 arranged in pairs on opposite sides thereof, one pair of wheels lying within the recess 21 adjacent the shoulder 22, and the other adjacent the proximate ends of the teeth which form the rack 23; each of these wheels is suitably 95 connected to the carriage as by means of 100 105

a bolt 28, spacing blocks 29 being employed to maintain the wheels a proper distance from each carriage end 24. By the means just described, the carriage is secured to the forward side of the press so as to be free for reciprocation thereupon.

Arranged within the seats 25 of the carriage are two head plates 30 in which are mounted a plurality of systems of rollers, four being the number shown (see Fig. 7), each adapted to function in the printing of a distinct color. As each roller system is like the others a description of but one is necessary. Composing each system are three rollers arranged in a row, and designated respectively as 31, 32, and 33 in the order of their distance from the bed of the press. All three rollers may be of solid construction, but the outer ones, 31 and 33, are covered by a tubing 34 of rubber, or some material which imparts to them properties similar to a composition coating. These three rollers are in frictional contact such that they drive one another, and their ends are formed with trunnions 35 that are journaled within suitable openings in bearing plates 36. Each system of three rollers is grouped with a second system by a hinge connection 37 between two of the bearing plates 36, this connection also extending to the proximate head plate 30 as clearly shown in Fig. 3.

At one end of the carriage the two bearing plates 36 are spaced apart sufficiently to accommodate between them a train of gears best shown in Fig. 8. One gear is carried fast upon the end of each roller, making three altogether for each system, their designations being 38, 39, and 40, respectively, for the rollers 31 to 33 inclusive. The several rollers comprised in the two groups of systems are interconnected through an intermediate gear 41 which is mounted coaxially with the hinge connection 37 between the bearing plates 36 so as to mesh with the proximate gears 38. This gear 41 is also engaged with another gear 42 which is mounted on the carriage and which is in mesh with the rack 23 so that as the carriage is reciprocated upon the guides 20, all the rollers in the two groups of systems are positively driven through the medium of the gears 41 and 42.

In association with the rollers that have been described, I provide a means for supplying to each system of rollers a distinct color of ink. As best shown in Fig. 7, use is made of a block 45 which is arranged adjacent the several rollers 33 for the major portion of their length. This block is held in place between the bars 26 as by means of screws 46. Viewed from the outer side, as in Fig. 2, this block presents a number of slots 47 each tapering inwardly toward the inner side of the block (see Fig. 7)

where it communicates with a circular groove 48 extending for something less than 180°. The walls of each slot, furthermore, are disposed at unequal angles relative to the outer side of the block 45 so that each slot points generally in a downward direction as viewed from the outer side of the block. From this it results also that at the juncture of each slot with its associated groove 48 there is formed a sharp knife-like edge 49, the opposite edge being relatively blunt. The several grooves 48 are disposed for the length of the block and each is arranged to accommodate an inking roller 50 that is mounted to revolve with its opposite ends supported in the two head plates 30. A recess 51 is also provided on the inner face of this block, one between each pair of inking rollers 50 so as to provide the necessary clearance for the proximate printing rollers 33.

Associated with the block 45 are other blocks 52, 53, and 54, the former intermediate of the two central rollers 50, and the other two to the outside thereof. The block 52 may be secured in place as by means of a bolt 55 which connects with the block 45, while the other blocks 53 and 54 are held in position by bolts 56 which enter the bars 26. Each of the three blocks last described is formed with a circular groove 57 less than 180° in cross section and in complementary relation to one of the grooves 48 in the block 45, so as to provide a surface extending around each of the inking rollers for most of its periphery.

Referring now to Figs. 10 to 15 inclusive, it will be noted that the inner faces of the blocks thus surrounding the inking rollers are formed with certain cuts 58 to provide parallel channels which run obliquely and cross-wise of the longitudinal grooves 48 and 57. In the case of the block 45 these cuts are intercepted by the longitudinal slots 47, but otherwise are similar to those in the other blocks, and preferably the depth of each cut is such as to provide a flat bottom (see Fig. 15) that is substantially tangent to the associated groove 48 or 57, as the case may be. When the blocks 52, 53, and 54 are assembled upon the outer block 45, the angular relation of the grooves 57 are reversed so that the surfaces which lie against the inking rollers 50 present a plurality of grooves, some disposed one way and some the opposite way, as indicated by the dotted lines in Fig. 14.

The inking rollers 50 are positively driven with reciprocation of the carriage through the instrumentality of a train of gearing, best shown in Fig. 9. Arranged upon one end of each inking roller is a gear 60 in mesh with a second gear 61 which in turn is drivingly connected with another gear 62 that derives motion from

a gear 63 that is mounted on the carriage with its teeth in mesh with the rack 23. A similar train of gears is used for each of the inking rollers, except that a single train 5 is provided for the two intermediate ones, the gear 61 being in mesh with each of the two proximate gears 60. It will now be apparent that I have provided means not only for positively rotating the inking rollers, but for rotating at the same time the printing rollers which are operatively related thereto.

In addition to the mechanisms described, means are provided for delivering at desired 15 intervals a regulated supply of ink to each system of printing rollers from the inking roller associated therewith. As best shown in Fig. 2, the bed of the press carries a chase frame 65 which provides a mounting for 20 the form or type. The side rails of the chase frame are each formed with a plurality of grooves 66 preferably undercut, in each of which is mounted a track 67, as best shown in Fig. 3, these tracks in each rail 25 corresponding in number to the systems of inking rollers that are mounted in the carriage. By forming each track with a dovetailed, or enlarged base which interlocks with the undercut groove, it may be moved 30 therein only in an endwise direction. Each groove is shown to terminate as at 68 (see Fig. 2), thus providing a stop which limits sliding movements of the track in one direction, and removable stop means are also 35 provided at the other end of the chase frame comprising a plate 69 detachably secured in place and arranged to overlie the proximate ends of the grooves adjacent thereto.

By reference to Fig. 8, wherein a portion 40 of the guide block 20 is broken away, it will be noted that the contact face of the track 67 is depressed as at 70 for a desired distance. These depressions will occur according to a prearranged plan so as to have 45 the effect of cams in shifting the form roller toward and from the bed of the press, and for each track so formed there will be an exact duplicate on the opposite side of the chase. Co-operating with each track is a 50 wheel 71 that is mounted on the printing roller 31, this wheel being adapted to ride upon the surface of the track and to drop into each depressed portion therein. Each of these wheels may be mounted in place in 55 some such manner as is suggested in Fig. 4 wherein the printing roller is provided with a shoulder 72 formed by reducing the diameter of the roller for a desired distance, the wheel 71 being held against the shoulder as 60 by means of a sleeve 73 which is fitted tightly over the reduced portion of the roller. In this manner each wheel may freely revolve, but may not shift its position upon its associated roller.

It will be noted that each roller 31 is

equipped with two wheels 71, one near each end, and each arranged to ride upon companion tracks. Owing to the fact that the roller 31 is in frictional contact with the one adjacent thereto, and that the wheel 71 70 is of large diameter as compared with the roller upon which it is mounted, I have formed in the adjacent roller 32 an annular recess 75 (see Fig. 3) for the accommodation of the wheel. In this manner the parts 75 are permitted to operate in their intended relation without interference.

The bearing plates 36, as already explained, are hinged two of them together so as to co-relate two systems of printing rollers. Normally the free ends of these plates 36 are held apart through the medium of springs 76 (see Fig. 9) having one end of each connected to the head plate 30, and the other end to the proximate bearing plate 36. The effect of this arrangement is normally to hold each system of rollers swung over in position to maintain contact between the inking roller 33 and the proximate printing roller 50, thus obtaining a constant 90 transfer of ink therebetween.

The operation of the mechanism hereinbefore described is substantially as follows:

First of all the press is equipped with a reciprocable carriage having suitable guides and racks to co-operate therewith. Within the chase is secured the form or type to which the different colors are to be applied, the letters W, X, Y, and Z, in Fig. 2, representing various portions of the type each 95 adapted to receive a different color. Each of the slots 47 within the block 45 is then filled with a desired color of printer's ink, and from these slots the ink is taken onto the rollers 50 along which it is evenly distributed through the aid of the grooves 48 and 57 which are reversely inclined. The roller having a rotary motion, and the ink slots being cut at an angle and remaining stationary, these grooves act as a knife in the usual form of ink fountain. The roller having one motion on the downward stroke of the carriage reverses this motion on the upward stroke. For this reason the sharp edge 49 acts as a knife on one motion, the slot serving as a receptacle waste groove on the reverse motion, carrying the overplus, if any, back and away from the roller. In this manner the spread of ink is controlled by the roller to the required film desired, making it certain that the distribution of ink is uniform and controlled at all times.

In the operation of the carriage each roller system is independently tilted to present the outermost printing roller 33 in contact with the inking roller 50 and at the same time to shift the printing or form roller 31 into contact with a desired portion of the type. These two ends are accomplished simultaneously by the means which 125

have been described. The normal tendency of each spring 76 is to tilt its associated roller system into contact with one of the inking rollers 50, but this condition may 5 obtain only when the two wheels 71 associated with each system are riding in depressed portions 70 of companion tracks. At all other times, as shown at the right hand end of Fig. 8, the wheels 71 hold the 10 bearing plates, together with the roller system therein mounted, away from contact with the associated ink roller 50, and also away from the face of the type. This results from the fact that each roller system 15 is hinged to swing about the axis of the gear 41, the force which induces such tilting proceeding from a point which is ahead of this hinged connection.

It is important to note that the three 20 inking rollers forming a single system are peculiarly constructed in that the two which lie to the outside are coated with rubber or a composition material, while the surface of the intermediate roller is metallic. In the 25 operation of the carriage the ink which is transferred from the inking roller 50 to the proximate printing roller 33 is distributed therefrom by compression to the metal roller 32, which further equalizes the film of 30 ink as it is deposited upon the form roller 31. This makes a perfect distribution, theoretically, because the ribbon or film of ink is first cut by the criss-cross grooves in the blocks surrounding the inking roller, and 35 then deposited onto the printing rollers by contact. As the inking roller and printing roller 33 are running in opposite directions, the ink is reduced to a film; from this inking roller to the metal or control roller 32 40 and thence to the form roller 31, the ink is compressed and distributed during the process of transfer. The film or ribbon of ink at this point is controlled to the required thickness of the film necessary to obtain 45 good printing, whether the form be a light one or heavy one, and the film is uniform by reason of the rotary motion of the form roller 31 against the control roller 32 which revolves against the composition roller, this 50 in turn revolving against the supply or ink roller 50. It is obvious that a new film of ink is presented to the face of the type at each revolution of the rollers, in consequence of which a new film is deposited, thereby 55 doing away with the necessity of carrying an overplus of ink as is customary with present printing presses now in use.

With an attachment of the kind described, 60 multicolor printing may be obtained in a very expeditious and satisfactory manner. To obtain border or panel printing the tubing 34 on one of the form rollers may be cut down to a desired length, or be located toward one end of the roller, or be arranged 65 thereon in sections spaced apart to

produce the desired effect. The possible arrangements of the tubing are almost without limit. Also the tracks which have the function of cams for the various roller systems may be formed with depressed portions 70 arranged in any desired manner, and substitution of one pair of tracks for another may readily be made in the manner already indicated so as to thereby confine the color printing done by each form roller 75 to a desired section of the type.

I claim:

1. In combination with a printing press provided with a rack, a reciprocable carriage in operative relation to the rack, a plurality of systems of inking rollers mounted in the carriage, each system being a unit and comprising a first composition roller, a metallic roller in contact therewith, and a second composition form roller in contact with the metallic roller and adapted to bear upon the face of the type, a positive driving connection between each of the rollers, a gear mounted on the carriage in mesh with the rack and arranged to drive the roller system, an inking roller in proximity to the first composition roller, tension means tending normally to hold the said composition roller in contact with the inking roller and also to maintain the form roller in contact with the type, and positively acting means adapted to shift the system of inking rollers at desired intervals in the travel of the carriage across the type to thereby remove the form roller from contact therewith, and also to remove the composition roller from contact with the inking roller, each of the systems of inking rollers being similarly constructed and having similar but independent operation, substantially as described. 90

2. In combination with a printing press, a carriage adapted for reciprocation thereon, a chase mounted on the press, a plurality of tracks arranged in parallelism upon opposite sides of the chase, each track being formed with a depression having a pre-arranged length and location to provide in effect a cam, an ink supply mounted on the carriage, and means for transferring the ink to the type including a device arranged to engage the tracks and permitting a transfer of the ink only when the device is seated within said depressions therein, substantially as described. 100

3. In combination with a printing press, a carriage adapted for reciprocation thereon, an ink supply mounted on the carriage, and a means for transferring the ink to the type comprising a system of contacting rollers, bearing plates in which the rollers are mounted, a pivotal support in the carriage for the bearing plates, means for normally holding one roller in operative relation to the ink supply and another roller in operative relation to the type, and means for tilt- 115 120 125 130

ing the bearing plates at desired points in the travel of the carriage to thereby remove one inking roller from operative relation with the type and another from operative 5 relation with the ink supply, substantially as described.

4. In combination with a printing press, a carriage adapted for reciprocation thereon, a system of printing rollers mounted in 10 the carriage and arranged to deliver ink to the type, a rotatable inking roller mounted in the carriage, and a block surrounding the roller for the major portion of its periphery, there being in the block an ink slot communicating with the roller, one of the slot edges adjacent the roller being relatively sharp to provide a knife edge, the surfaces of the block surrounding the roller being also formed with a series of oblique grooves 15 some slanting one way and some the other, and each independent of the rest, whereby the ink is distributed through such grooves from one end of the inking roller to the other, the knife edge acting to remove the 20 overplus of ink when the roller is revolved in one direction, substantially as described.

5. In combination with a printing press, a carriage adapted for reciprocation thereon, a system of inking rollers mounted on 25 the carriage, one roller—the form roller—being arranged to transfer ink to the type, a pair of wheels idly mounted on the form roller near opposite ends thereof, a chase mounted on the press, tracks for the form 30 wheels arranged on opposite sides of the chase, there being depressions in the tracks at desired intervals into which the wheels may lower, the roller system being pivotally held as a unit so as to tilt with each 35 lowering of the form wheels in the track depressions to thereby move the form roller into contact with the type, and means for delivering ink to the roller system only when the form roller is in contact with the 40 type, substantially as described.

6. In combination with a printing press, a carriage adapted for reciprocation thereon, and means detachably secured within the carriage adapted to transfer a plurality 45 of different colored inks to certain selected portions of the type as the carriage is reciprocated upon the press, said means acting also to shut off the supply of each color of ink except when the same is in process 50 of transfer to the type, substantially as described.

7. In combination with a printing press, means for delivering ink to the type including two inking rollers, a system of transfer rollers in operative relation to each inking 60 roller, one of said transfer rollers being arranged operatively to the type, means for moving both systems of inking rollers across the face of the type, a common driving connection between all of the transfer rollers of 65 both systems, and means for moving either system of rollers toward and from the type and simultaneously toward and from its associated inking roller without affecting the driving connection with the other roller 70 system, substantially as described.

8. In combination with a printing press, means for inking the form including an inking roller, a composition roller in contact therewith, a metallic roller in contact 75 with the composition roller, and a second composition roller in contact with the metallic roller and adapted to engage the form, means for positively rotating the two composition rollers and metallic roller therebetween, and means for moving the form 80 roller relative to the type, substantially as described.

9. In combination with a printing press, means for inking the form including an inking roller, a system of transfer rollers arranged adjacent thereto, a mounting for said system as a unit comprising bearing plates 85 movably arranged with respect to the inking roller and to the form whereby the roller 90 system may simultaneously be brought into contact with the type and inking roller or be disengaged therefrom, substantially as described.

10. In combination with a printing press, means for inking the form including two inking rollers, a system of transfer rollers in operative relation to each inking roller, one of said transfer rollers in each system being arranged operatively to the form, 95 means for moving both systems of inking rollers relative to the form, a common driving connection between all the transfer rollers of both systems, and means for moving either roller system into or out of engagement with the form and its associated inking roller without affecting the driving connection with the other roller system, substantially as described.

HERMAN A. AGRICOLA, Jr.

Witness:

W. F. CRUSSELLE.
